United States Patent

Des. 236,606
Patented Sept. 2, 1975

236,606

TRUCK CAB

John M. Bodden, Bellevue, Wash., assignor to
Paccar Inc., Bellevue, Wash.

Filed Nov. 19, 1973, Ser. No. 417,186

Term of patent 14 years

Int. Cl. D12—08

U.S. Cl. D12—96

FIG. 2

FIG. 1

FIG. 3

FIG. 4

FIG. 1 is a front elevational view of a truck cab showing my new design;

FIG. 2 is a side elevational view thereof, the opposite side being a mirror image of the side shown herein;

FIG. 3 is a perspective view thereof; and

FIG. 4 is a rear elevational view thereof.

The broken lines in the drawing are for illustrative purposes only.

I claim:

The ornamental design for a truck cab, as shown and described.
